RADIO PHONOGRAPH CABINET

Clyde A. Peterson, Dewart, and Harold W. Schaefer, Sunbury, Pa., assignors to Westinghouse Electric Corporation, East Pittsburgh, Pa., a corporation of Pennsylvania

Application July 7, 1949, Serial No. 103,384

7 Claims. (Cl. 179—100.12)

1

This invention relates to radio receiving and recording playing apparatus and more particularly to a combination radio receiver-record player and a cabinet therefor.

An object is to provide improved radio receiving and record playing apparatus.

A further object is to provide an improved radio and record playing combination.

A still further object is to provide an improved combination radio receiver-record player combination and cabinet therefor.

A more specific object is to provide an improved combination of radio receiving-record playing apparatus and a cabinet in which the apparatus is enclosed wherein a single door or closure serves to move the record playing apparatus into and out of the cabinet and also provides access to the controls of the radio receiving apparatus when the record playing apparatus is in its normal position within the cabinet.

These and other objects are effected by our invention as will be apparent from the following description and claims taken in connection with the accompanying drawings forming a part of this application, in which:

Figure 1 is a partial side elevation, with parts of the cabinet broken away, of a radio receiving and record playing combination embodying our invention;

Fig. 2 is a partial front perspective view, with parts of the cabinet broken away, with the closure in position to permit operation of the controls for the radio receiving apparatus;

Fig. 3 is a partial front perspective view with the closure in closed position;

Fig. 4 is a partial front perspective view with the record playing apparatus partially out of the cabinet;

Fig. 5 is a partial front perspective view, with parts of the cabinet broken away, of a second embodiment showing the closure in position to permit operation of the controls for the radio receiving apparatus;

Fig. 6 is a partial front perspective view, similar to Fig. 5, with the record playing apparatus partially out of the cabinet; and

Fig. 7 is a sectional view of a detail.

Referring now to the drawings in detail, the reference character 10 indicates a cabinet which is adapted to house a radio receiving set 11 and a record player 12. Like reference characters indicate like parts in the various figures of the drawings.

Figs. 1, 2, 3 and 4 illustrate one embodiment of my invention. In this embodiment, the cabinet 10 comprises a pair of side walls 14 and 15, a rear wall 16, a front wall 17, a top wall 18, and a bottom wall which is not shown. The walls 14, 15, 16, 17, 18 and 19 form an enclosure for housing the radio receiving set 11 and the record player 12. The front

wall 17 has an opening 20 therein for permitting access to the radio receiving set 11 and the record player 12. The opening 20 is closed by a door or closure 21 which functions in a manner which will be fully described hereinafter. The record player 12 is shown in its normal position in the cabinet 10 in Figs. 1, 2 and 3.

The radio receiving set 11 is of a conventional type and comprises the usual chassis 22, having the usual transformers 23, amplifying tubes 24 and condensers 25, mounted thereon. The radio receiving set 11 is mounted on the inside of the cabinet 10 on the front wall 17 by means of a bracket 26 and inclines downwardly from the opening 20 in the front wall 17. The bracket 26 extends upwardly and rearwardly from the opening 20. The front side of the bracket 26 is visible from the front of the cabinet and a broadcast frequency dial 27 is graduated thereon. An indicator 28 is synchronized with the tuning element of the radio receiving set and extends through the bracket 26. A tuning control 29 for tuning the receiving set 11 to the desired frequency extends through the bracket 26 and is accessible from the front of the cabinet 10 through the opening 20. The indicator 28 is moved along the dial 27 by turning the tuning control 29. A control 30 which is used for turning the power to the radio receiving set 11 on and off and for regulating the volume of the radio receiving set 11 and a control 31 for regulating the tone extend through the bracket 26. The controls 30 and 31 are also accessible from the front of the cabinet 10 through the opening 20. The audio output from the radio receiving set is connected to a loud speaker 32 which is mounted on the front wall 17 of the cabinet 10.

From the above description it is seen that the dial 27, pointer 28, tuning control 29, power switch and volume control 30, and tone control 31 are all visible and accessible for adjustment from the front of the cabinet 10 through the opening 20 in the front wall 17 thereof.

The record player 12 may be of a conventional type and comprises a platform 35, a turntable 36 for supporting records to be played thereon, a center post 37 for centering records to be played, and a pick-up mechanism 38 for picking up intelligence from a record. A motor for rotating the turntable 36 is usually mounted under the platform 35. The motor is usually connected to a suitable source of power through some well known means. The output from the pick-up mechanism 38 is connected to the audio amplifier of the radio receiving set 11 through a conductor 40. The audio amplifier amplifies the intelligence picked up by the pick-up mechanism and reproduces it through the loud speaker 32 of the radio receiving set 11.

The record playing apparatus 12 is supported

in the cabinet 10 above the radio receiving set 11 by means of two sets of rails 42 and 43. A rail 41 is mounted on the inside of each of the side walls 14 and 15 of the cabinet 10 at substantially equal elevations, and at substantially the same elevation as the bottom of the opening 20 in the front wall 17 of the cabinet. A rail 43 is attached to each side of the platform 35, substantially opposite each other. The rails 43 are substantially rectangular in cross section and each of the rails 42 have a substantially rectangular slot 44 therein for receiving one of the rails 43. The rails 42 and 43 provide a slide arrangement which permits an operator to slide the record playing apparatus 12 into and out of the cabinet 10 through the opening 20 in the front wall 17 thereof. The rails 42 and 43 may be attached to the cabinet 10 and record playing apparatus 12 in any suitable manner, such as, with screws or the like.

A bracket 46, having an off-set arm portion 47, is rigidly attached to each side of the platform 35 at the front thereof. The upper ends 48, of each of the off-set portions 47 of the brackets 46, are pivotally attached to opposite sides of the closure 21, near the top thereof by pins 49. A strap 50 is fixedly attached to the closure 21, near the top thereof, opposite each of the arms 47. The inner ends of the straps 50 have U-shaped portions 51 formed thereon, which U-shaped portions 51 extend around the arm portions 47 of the brackets 46. The closure 21 is provided with a handle 52 for moving it back and forth.

When it is desired to load records on the turntable 36 for playing, the operator simply pulls outward on the handle 52. The brackets 50, U-shaped portions 51 of brackets 50, and arm 47 of bracket 46 transmits the pull to the platform 35 and causes the record player 12 to slide along the rails 42 and 43 to the desired outward position, such as indicated in Fig. 4. After the turntable 36 has been loaded with records, the record player 12 may be returned to its normal position within the cabinet 10, as shown in Figs. 1 and 3, simply by pushing inward on the handle 52. After the record playing apparatus has been returned to the inside of the cabinet 10, it is desired to adjust the controls 29, 30 and 31 of the radio receiving set 11. This may be accomplished by pushing still further inward on the handle 52. The pins 49 permit the closure 21 to pivot thereabout so that the lower end 53 of the closure 21 moves into the cabinet 10, as indicated in Fig. 2. It is seen that with the closure 21 in the position shown in Fig. 2 the operator has access to the controls 29, 30 and 31 for adjusting or manipulating the same. After the controls 29, 30 and 31 have been adjusted, the closure 21 may be moved to a position substantially flush with the front wall 17 of the cabinet 10, as indicated in Fig. 3, simply by pulling slightly outward on the handle 52. In this position of the door 21 all controls are completely hidden from outside the cabinet 10. The pins 49 provide just enough friction between the arms 47 of the brackets 46 and the edges of the closure 21 to hold the closure 21 in any inclined position to which it is adjusted.

The embodiment shown in Figs. 5 and 6 is similar to the previous embodiment, except, instead of pivoting the closure 21 to the record playing apparatus, the closure 21 is fixedly attached in a vertical position to the platform 35. The record 12 is moved into and out of the cabinet by pushing inward or pulling outward on the handle 52

as in the previous embodiment. However, in this embodiment the rails 42 are longer than in the previous embodiment to permit moving the radio apparatus far enough back into cabinet 10 to permit access to the controls of the radio receiving set. To gain access to the controls 29, 30 and 31 the operator simply pushes back on the handle 52 to move the record player horizontally back into cabinet 10 to a position such as indicated in Fig. 5. After the controls 29, 30 and 31 have been adjusted to the operator's satisfaction, the closure 21 is again pulled back flush with the front wall 17 of the cabinet 10, as shown in Fig. 3. A spring loaded pin 54 is provided on each of the rails 43 and a slot 55 is provided in each of the rails 42. The pin 54 snaps into the slot 55 when the record player 12 reaches a position in the cabinet 10 where the closure 21 is substantially flush with the front wall 17. The pin 54 and slot 55 serve to lock or detain the record player 12 in this position which is its normal position in the cabinet 10. However, pressure on the handle 52 in either of the two operating directions will cause the pin 54 to ride out of the slot 55 and permit the record player 12 to slide on the rails 42 and 43.

It is understood that if it is desired to use the radio receiving set 11 to the exclusion of the record player 12, access may be had to the controls 29, 30 and 31 of the radio receiving set 11, in each embodiment, simply by pushing inward on the handle 52 to move the closure 21 to the position shown in Fig. 2 or 5. After the controls have been adjusted, the closure 21 may be moved back to the position shown in Fig. 3.

There are many advantages of our invention. By mounting the record player 12 above the radio receiving set 11 and providing a single closure 21 for gaining access to both, a more economical console type radio-record player combination may be produced. The arrangement provided permits easy access to all of the controls which ordinarily require adjustment during operation of such apparatus; however, the controls are completely hidden from the operator when they are not being adjusted. It is desirable to cover the controls for many reasons. Besides adding to the aesthetic features of the combination, it is desirable to make it impossible for small children to manipulate the controls and possibly receive a severe shock by touching a faulty control.

While we have shown our invention in several forms, it will be obvious to those skilled in the art that it is not so limited, but is susceptible of various changes and modifications without departing from the spirit thereof, and we desire, therefore, that only such limitations shall be placed thereupon as are specifically set forth in the appended claims.

We claim as our invention:

1. In a cabinet for radio receiving and record playing apparatus, a wall having an opening therein, a radio receiving set having adjustable controls mounted inside said cabinet with said controls adjacent said opening, record playing apparatus located in said cabinet above said radio receiving apparatus, a closure for said opening attached to said record playing apparatus, means including said closure for moving said record playing apparatus into and out of said cabinet through the opening in said wall, said closure being substantially flush with said front wall when said record playing apparatus is in normal position in said cabinet, said closure being adapted to be further moved into said cabinet from a

position substantially flush with said wall of said cabinet to permit access through said opening to said controls for said radio receiving set.

2. In a cabinet for radio receiving and record playing apparatus, a front wall having an opening therein, a closure for said opening, a radio receiving set having adjustable controls mounted in such manner that said controls are adjustable through said opening, record playing apparatus attached to said closure for said opening and mounted in said cabinet above said radio receiving apparatus, means including said closure for moving said record playing apparatus into and out of said cabinet through said opening, and pivot means attaching said closure to said record playing apparatus so that when said record playing apparatus is in normal position in said cabinet said closure is substantially flush with said front wall of said cabinet, said pivot means being so constructed and arranged that a portion of said closure may be further moved into said cabinet from a position substantially flush with said front wall of said cabinet to permit access through said opening to said controls for said radio receiving set.

3. In a cabinet for radio receiving and record playing apparatus, a front wall having an opening therein, a closure for said opening, a radio receiving set having adjustable controls mounted in said cabinet with said controls adjacent said opening, record playing apparatus attached to said closure for said opening and mounted in said cabinet above said radio receiving apparatus, means including said closure for moving said record playing apparatus into and out of said cabinet through said opening, and means pivoting the upper portion of said closure to said record playing apparatus so that when said record playing apparatus is in normal position in said cabinet said closure is substantially flush with said front wall of said cabinet, said pivot means being so constructed and arranged that the lower portion of said closure may be further moved into said cabinet from a position substantially flush with said front wall of said cabinet to permit access through said opening to said controls for said radio receiving set.

4. In a cabinet for radio receiving and record playing apparatus, a front wall having an opening therein, a closure for said opening, a radio receiving set having adjustable controls mounted inside said cabinet with said controls adjacent said opening, record playing apparatus attached to said closure for said opening and mounted in said cabinet above said radio receiving set, means including said closure for moving said record playing apparatus into and out of said cabinet through said opening, and means attaching said closure to said record playing apparatus, said attaching means including an arm attached to said record playing apparatus and pivot means connecting said arm to an upper portion of said closure, said pivot means being so constructed and arranged that the lower edge of said closure may be moved into said cabinet from a position substantially flush with said front wall of said cabinet to permit access through said opening to said controls for said radio receiving set.

5. In a cabinet for radio receiving and record playing apparatus, a front wall having an opening therein, a closure for said opening, a radio receiving set having adjustable controls mounted in said cabinet with said controls adjacent said opening, record playing apparatus attached to

said closure for said opening and mounted in said cabinet above said radio receiving set, means including said closure for moving said record playing apparatus into and out of said cabinet through said opening, means attaching said closure to said record playing apparatus, said attaching means comprising an arm attached at its lower end to said record playing apparatus, means pivotally connecting the upper portion of said arm to said closure, and a member extending from said closure to a portion of said arm intermediate said lower end and said upper portion of said arm, said attaching means being so constructed and arranged that the lower edge of said closure may be moved into said cabinet from a position substantially flush with said front wall of said cabinet to permit access through said opening to said controls for said radio receiving set.

6. In a cabinet for radio receiving and record playing apparatus, a wall having an opening therein, a closure for said opening, a radio receiving set having adjustable controls mounted inside said cabinet with said controls adjacent said opening, record playing apparatus attached to said closure for said opening and mounted in said cabinet above said radio receiving apparatus, means including fixed rails and movable rails for mounting said record playing apparatus in said cabinet, means fixedly attaching said closure to said record playing apparatus so that when said record playing apparatus is in normal position in said cabinet said closure is substantially flush with said front wall of said cabinet, means for detaining said record playing apparatus in normal position within said cabinet with said closure substantially flush with said front wall of said cabinet, said detaining means being so constructed and arranged that said closure may be further moved into said cabinet from a position substantially flush with said front wall of said cabinet to permit access through said opening to said controls for said radio receiving set.

7. In a cabinet for radio receiving and record playing apparatus, a wall having an opening therein, a closure for said opening, a radio receiving set having adjustable controls mounted inside said cabinet with said controls adjacent said opening, record playing apparatus attached to said closure for said opening and mounted in said cabinet above said radio controls, means attaching said closure to said record playing apparatus so that movement of said closure in one direction moves said record playing apparatus out of said cabinet and movement of said closure in a direction toward the inside of said cabinet exposes said controls for said radio apparatus so that they may be adjusted through said opening in the front wall of said cabinet.
